RESET AND AUTOMATIC IGNITION MECHANISM
FOR THERMOELECTRIC SAFETY SHUT-OFF
DEVICES

John H. Thornberry, Whitefish Bay, Wis., assignor to Milwaukee Gas Specialty Company, Milwaukee, Wis., a corporation of Wisconsin

Application December 13, 1950, Serial No. 200,548

5 Claims. (Cl. 158—128)

This invention relates, in general, to thermoelectric control devices, and has particular relation to an improved reset and automatic ignition mechanism for thermoelectric safety shut-off devices.

While the particular device which will be hereinafter described in connection with the drawings is a thermoelectric safety shut-off valve, it is to be understood that the present invention is not limited to use with this particular type of device, but may be employed with thermoelectric safety switches and all similar devices as suitable or desired.

The present invention may be more particularly characterized as relating to devices of the character disclosed and claimed in the copending application of Oscar J. Leins, Serial No. 200,615, filed December 13, 1950.

According to the invention to which the foregoing application of Oscar J. Leins is directed, there is provided in conjunction with a manually operable finger piece or actuator, an energy storing device in which energy is stored by simple manipulation of the actuator, and time delay mechanism which operatively cooperates with the energy storing device for providing a time delay between energization of the energy storing device and resetting of the armature to attracted position and the controlling member to operating position by the energy storing device.

One of the main objects of the present invention is to provide ignition means having a switch operatively cooperating with the operating connection between such energy storing device and the valve or other controlling member for automatically igniting the pilot burner by the action of the energy storing device as it operates to reset the armature to attracted position and the valve or other controlling member to operating position.

An advantage of the invention resides in the establishment of a flow of fuel to the pilot burner and automatic ignition of the pilot burner at commencement of the action of the energy storing device in its resetting operation to provide safe lighting should there be any tendency to open the safety shut-off valve slowly, and thereafter spend some time in fully opening such valve.

Another object of the invention is to provide a simple, compact and effective mechanism which will combine automatic ignition with an energy storing device which may be energized by a simple manual manipulation and without requiring the person operating the device to hold the armature in attracted position and the controlling member in operating position for a prolonged period of time.

Further features and advantages and numerous adaptations of the invention will be apparent from the following detailed description and the accompanying drawings.

In the drawings:

Figure 1 is a sectional view, partially in elevation, of one illustrative embodiment of the invention, taken along the line 1—1 of Figure 2, and showing more or less diagrammatically the thermoelectric generator and its circuit, the main burner, the pilot burner, and the electric igniter therefor;

Figure 2 is a fragmentary sectional view, partially in elevation and partially diagrammatic, taken along the line 2—2 of Figure 1;

Figure 3 is a more or less schematic exploded view showing the principles of operation of the device;

Figure 4 is a fragmentary sectional view through the by-pass valve mechanism for the pilot burner;

Figure 5 is an elevational view of the cam guide;

2

Figure 6 is another elevational view of the cam guide taken at right angles to Figure 5; and

Figure 7 is an elevational view of the cam shaft showing the position of the cam thereon.

Referring now to the drawings, the embodiment of the invention selected for illustration comprises a valve body or casing 1 having a fuel inlet 2 for receiving suitable gaseous fuel and a fuel outlet 3 for delivering the gaseous fuel, for example, to a main burner.

Internally the valve body 1 has a partition 4 provided with a valve opening 5 for placing the inlet chamber 6 in communication with the outlet chamber 7. An annular valve seat 8 surrounds the inlet side of the opening 5.

A hood 9 is clamped to the valve body 1 by a union 9' preferably with a hood gasket therebetween. The interior of the hood 9 may be separated and sealed from the interior of the inlet chamber 6, for example, by a guide member 10 having an axial opening 11 through which the valve stem 10' has reciprocatory movement with packing 12 to prevent leakage of gas along the valve stem 10' from the inlet chamber 6 to the interior of the hood, as shown in Oscar J. Leins Patent No. 2,126,564, patented August 9, 1938. These features per se form no part of the present invention, and therefore are not shown in detail in the drawings of the present application.

An electromagnet 13 is disposed within the hood 9 and comprises, for example, a U-shaped magnet frame 14 provided about one of its legs with a coil 15. The magnet frame 14 and a terminal bushing 16 may be rigidly secured to the outer end of the hood 9, for example, by a nut 17, as shown in Harold A. Mantz Patent No. 2,409,947, patented October 22, 1946. The lead comprises lead conductors 17 and 18 which, while shown diagrammatically, may be of concentric form as shown in the above identified Oscar J. Leins patent. At one end, the lead conductors 17 and 18 are connected in circuit with the coil 15. The opposite ends of the lead conductors 17 and 18 are connected in circuit with the thermoelectric generator elements 19 and 20 of a thermoelectric generator which, while shown in the form of a thermocouple, may be in the form of a thermopile, or of other suitable form.

The thermoelectric generator elements 19 and 20 are joined at 21 to form a hot thermojunction which may be positioned, for example, to be heated by the flame of a pilot burner 22 as long as the pilot burner is ignited. The pilot burner 22 is disposed, for example, in juxtaposition to a main burner 23 to ignite the same. A fuel supply pipe 24 leads from the outlet 3 to the main burner 23 for the delivery of gaseous fuel to the main burner, for example, through a mixing chamber 25 to which air is admitted, as well understood in the art.

An armature 26 is attached to the outer end of the valve stem 10 within the hood 9, and preferably in a manner to permit self-accommodation of the armature to the pole ends of the magnet frame 14 when the armature is in attracted position. A safety shut-off valve member 27 is attached to the opposite end of the stem 10' within the inlet chamber 6, and preferably in a manner to permit self-accommodation of the valve member 27 to its valve seat 8 when in closed position against the valve seat.

The supply of gas to the pilot burner 23 is under the control of a by-pass valve mechanism shown in detail in Figure 4. This by-pass valve mechanism comprises a bore or opening 28 in the valve body 1. This opening 28 is enlarged and internally threaded at one end at 29, and its opposite end is closed and of reduced diameter at 30. A valve plug 31 has an opening 32 extending axially therethrough, and an enlarged externally threaded end 33 which is screwed into the threaded opening 29 preferably with a suitable sealing gasket between the enlarged end 33 and a shoulder in the valve body.

A valve stem 34 extends through the axial plug opening 32 with annular clearance or space for the flow of gas therebetween, as will hereinafter appear. A valve member 35 is screwed on the inner end of the stem and is provided with a yielding valve facing 36 held thereto, for example, by a retainer 37. The valve facing 36 seats against an annular valve seat 38 at the inner end of the valve plug 31 when the valve stem 34 is in one

position, and moves to open position away from the valve seat 38 when the valve stem 34 moves inwardly. The opposite end of the valve stem 34 is guided for reciprocatory movement in the reduced diameter opening 30.

Between its ends the valve stem 34 has a valve member 39 integral therewith or fixed on the stem 34 for reciprocatory movement therewith. The valve member 39 has a yielding valve facing 40 held thereto, for example, by a retainer 41. The valve facing 40 seats against an annular valve seat 42 at the adjacent end of the valve plug 31 when the valve stem 34 is in position opposite that in which the valve facing 36 is seated against the valve seat 38. A coiled spring 43, interposed between the valve member 39 and a shoulder 44 in the valve body 1, acts to open valve member 35 from its valve seat 38 and to close the valve member 39 against its valve seat 42. The valve members 35 and 39 are preferably so arranged that the valve member 35 will open before the valve member 39 closes, and vice versa, for a purpose which will hereinafter appear.

Between its enlarged end 33 and the valve seat 42, the valve stem 34 has a pair of spaced annular flanges 46 between which is disposed an annular or O shaped sealing ring 47 of neoprene or other suitable material. This ring 47 contacts the inner periphery of the bore 28 and forms a gas seal for preventing the flow of gas from one side of ring 47 to the other side of the ring externally of the valve plug 31. The valve body 1 has a passage 48 which opens from the inlet 2 or upstream side of the valve body into the bore or opening 28 on one side of the ring 47. Another passage 49 in the valve body 1 constitutes a pilot fuel outlet, and opens from the bore or opening 28 on the other side of the ring 47 and delivers fuel to the pilot burner 22 through a fuel supply tube 50 leading to the pilot burner. The valve plug 31 has diametrical ports 52 which place the opening 32 in communication with the bore 28 on the side of the seal ring 47 from which leads the passage 49.

For the purpose of cocking or resetting the device, there is provided a drive shaft 54 rotatably supported in a wall of the valve body 1. The inner end of the shaft 54 extends inwardly into the valve body 1 and is connected to the coiled spring 55 of a clockwork mechanism designated in general at 56.

The clockwork mechanism 56 is shown only diagrammatically, it being understood that any suitable clockwork mechanism may be employed. Since clockwork mechanisms of this sort are well known in the art, suffice it to state that this mechanism has, for example, a suitable escapement such as also well known in the art and which, therefore, is shown only diagrammatically at 57. In the illustrated embodiment of the invention, the clockwork mechanism 56 serves as an energy or power storing device, and the escapement means serves as a time delay means whereby the armature 26 may be actuated to attracted position and the valve member 27 to open position by the energy in the clockwork mechanism after a time delay following energization of the spring 55, as will presently appear. The time delay is preferably for a predetermined period of time which will permit lighting of the pilot burner 22 and thermo-electric energization of the electromagnet 13 sufficiently to hold the armature 26 in attracted position and the valve member 27 in open position.

The time delay device shown of the spring-type may, for example, be of the form illustrated in Marcus H. Rhodes' Patent 2,274,635, patented March 3, 1942, or it may be of the form illustrated in Charles B. Simmons' Patent 2,258,474, patented October 7, 1941, or of any other suitable or preferred form. Interval timers of this sort are well known in the art and therefore a detailed illustration of the same is believed to be unnecessary in the present application.

The outer end of the shaft 54 extends outwardly from the valve body 1 and is provided with a knob or finger piece 58 which is adapted to be grasped in the hand of the person operating the device and turned to turn the shaft 54 in a direction to wind or tension the spring 55. The inner end of the shaft 54 fits telescopically for relative turning movement in a hollow cam shaft 60 which is rotatably supported in the valve body 1. The shaft 60 has an integral disc or radial flange 61. Mounted for relative turning movement on the drive shaft 54 and in proximity to the disc 61 is a ratchet wheel 62.

A drive wheel 63 is fixed on the drive shaft 54 for turning movement therewith. The wheel 63 is disposed in proximity to the ratchet wheel 62, and has a pair of diametrically opposite clutch claws 64 struck inwardly therefrom as the device is shown in Figure 2, for cooperation with a pair of diametrically opposite clutch claws 65 struck outwardly from the ratchet wheel 62. A coiled torque spring 66 is interposed between the ratchet wheel 62 and the disc 61, and is connected at its opposite ends to the ratchet wheel 62 and disc 61, for example, by engagement of its turned ends in openings in the ratchet wheel 62 and disc 61 as shown in Figure 2. A coiled spring 67 is interposed between the ratchet wheel 62 and disc 61, and acts endwise therebetween.

The cam shaft 60 has in the outer periphery of the disc 61 thereon a pair of diametrically opposite detent notches 70 for engagement with a humped detent portion 71 of a spring 72 for holding the cam shaft 60 in position. The opposite end of the spring 72 is fixedly anchored at 73, for example, on the valve body 1 within the outlet chamber 7. A cam follower 74 has a forked or bifurcated portion presenting arms 75 which are slotted at 76 and straddle the cam shaft 60. A cam 68 is fixed on the cam shaft 60 for rotation therewith, and has a pair of generally diametrically oppositely directed cam arms 79 which cooperate with the cam follower 74.

The cam follower 74 has an integral pin 80 which telescopes into and has sliding movement in the sleeve portion 81 of a valve disc screw 82. The valve disc 27 may, for example, be clamped between the polygonal head of the screw 82 and the head of a screw 83 the shank of which passes through the valve disc 27 and is screwed into the head of the valve disc 82. A coiled spring 84 is interposed between the head of the screw 82 and the cam follower 74, and acts endwise therebetween.

To cause ignition of the pilot burner 22 when flow of gas is established thereto, an electric igniter is provided. This igniter comprises, in general, a glow coil 100 in the form of a coiled wire or other suitable ignition element. Low voltage electric energy for energizing the ignition element 100 is supplied, for example, by a step-down or current limiting transformer 101. This transformer 101 comprises a line voltage primary 102 supplied by line wires 103 connected, for example, to a suitable source of commercial alternating current (not shown) such as may be adapted for supplying current at a voltage variation from about 105 to 115 volts. The secondary of the transformer 101 is indicated at 104.

Although the present invention is not limited thereto, the use of a transformer 101, which will supply about 20 to 24 volts for ignition purposes, is contemplated. The use of such a transformer permits the location of the same at a much greater distance from the appliance than is possible with a 1½-2½ volt transformer. This saves the cost of running a high voltage line to the appliance. Moreover, the cost of the igniter is thereby reduced because the same transformer may be used, for example, for energizing the igniter and for operating room thermostat or other control devices.

A switch 105 is positioned, for example, adjacent to the ratchet wheel 62 and comprises a fixed contact 107 and a movable contact 106. The movable contact 106 is connected to one side of the secondary 104 by a conductor 108. The fixed contact 107 is connected to one end of the ignition coil 100 by a conductor 109. The other end of the ignition coil 100 is connected by a conductor 110 to the other side of the secondary 104.

For the purpose of closing the switch 105 upon commencement of rotation of the drive wheel 63 under the action of the spring 55 of the clockwork mechanism 56 or other energy storing device, a plunger 111 is interposed between the movable contact 106 and the periphery 75 of the drive wheel 63. One end of the plunger 111 has operative cooperation with the contact 106, and the other end of the plunger has operative cooperation with the periphery of the drive wheel 63. When the wheel 63 is positioned as shown in Figure 3, a spring 112 acting, for example, against a flange 113 on the plunger 111 forces one end of the plunger into the adjacent notch 92 in the periphery of the wheel 63. Upon commencement of rotation of the wheel 63 by the energy storing device, the adjacent cam surface 94 at the adjacent notch 92 imparts rectilinear movement to the plunger 111 in

a direction to force the contact 106 into closed position in contact with the contact 107 to close the ignition circuit and energize the igniter 100.

The operation of the device is as follows:

When the pilot burner 22 is ignited, the heat thereof on the hot junction 21 of the thermoelectric generator produces a thermoelectric current in the coil 15. The magnet frame 14 and armature 26 are preferably formed of an alloy of relatively low magnetic reluctance. As a result, the minute or relatively weak electromotive force produces a magnetic field of sufficient strength so that when the armature 26 is placed in attracted position the magnetic attraction will hold the armature 26 in attracted position against the magnet frame 14 and the valve member 27 in open position. The holding action of the electromagnet 13 at this time is greater than the force exerted by a spring 90 which is interposed, for example, between the valve member 27 and the guide member 10 or packing 12, and acts endwise therebetween.

If the flame of the pilot burner 22 is extinguished, the holding action of the electromagnet 13 ceases to be sufficient to hold the armature 26 attracted to the magnet frame and the valve member 27 in open position. As a result, the spring 90 moves the valve member 27 to closed position against its valve seat 8 to shut off the supply of fuel to the main burner 23 and also the supply of fuel to the pilot burner 22, as will presently appear. The armature 26 moves to retracted position with the movement of the valve member 27 to closed position.

When it is desired to reset or cock the device, the knob or finger piece 58 is grasped and rotated, for example, from the position engaging a stop *a* as shown in dotted lines in Figure 3 into the position engaging a stop *b* as shown in full lines in the same figure. The accompanying rotation of the drive shaft 54 winds or tensions the spring 55 of the clockwork mechanism 56 to set up and store therein the power or energy necessary for resetting or cocking the armature 26 to attracted position and the valve member 27 to open position. The rotation of the drive shaft 54 which accompanies rotation of the knob 58 as above described, also turns the drive wheel 63 with the shaft 54 until the clutch claws 64 engage with the clutch claws 65 on the ratchet wheel 62 in such manner that the ratchet wheel 62 will be turned with the drive wheel 63 when the drive wheel 63 rotates in the opposite direction. The clutch claws 64 and 65 may be of spring or yielding form to permit the claws 64 to snap past and engage the claws 65 and to permit disengagement in the opposite direction, or the clutch claws may be of other suitable form to permit the desired action.

It is to be noted at this point that the only manual manipulation required to cock or reset the device is to turn the knob 58 to wind or tension the spring 55. The person operating the device may then immediately remove his hand. He is not required to hold the armature in attracted position and the valve member in open position until the electromagnet is energized sufficiently to accomplish this result.

As soon as the knob 58 is released, the spring 55 of the clockwork mechanism drives or turns the shaft 54 in the reverse direction with accompanying turning movement of the ratchet wheel 62 in the same direction through the cooperating clutch claws 64 and 65. When the valve member 27 is closed, the outer end of the valve member 35 engages in one of a pair of diametrically opposite notches 92 in the periphery of the ratchet wheel 62, and, as a result the spring 44 closes the valve 39 and opens the valve 35 of the by-pass valve mechanism for the pilot burner.

At the same time (i. e., when the valve member 27 is closed) the inner end of the plunger 111 engages in the other notch 92 in the periphery of the drive wheel 63. As a result, the movable contact 106 is positioned in open circuit position as shown in Figure 3, for example, by its inherent resilience biased in such direction or under the action of the spring 113 where the plunger 111 is connected to the contact 106, or otherwise as desired. The ignition circuit is thus open, and the igniter 100 is deenergized.

Upon commencement of rotation of drive wheel 63 the cam surface 94 at the adjacent peripheral notch 92 will actuate the valve stem 34 in a direction against the action of the spring 44 and thus move the valve 35 to closed position and the valve 39 to open position. Fuel then

passes from the upstream side of the valve body 1 through passage 48, bore 28, opening 32, ports 52, passage 49, and tube 50 to the pilot burner which may be ignited, for example, by the igniter coil 100 as will next appear.

Also at the same time (i. e., upon commencement of rotation of the drive wheel 63 by the clockwork mechanism) the cam surface 94 at the other peripheral notch 92 will actuate the plunger 111 outwardly and thereby close the contact 107 into contact with the contact 106. This closes the ignition circuit and energizes the igniter 100. As a result, when gaseous fuel issues from the pilot burner ports, it is ignited by the igniter 100. This assures safe lighting because, should there be any tendency for the clockwork mechanism to open the shutoff valve 27 slowly and thereafter spend some time in fully opening the valve 27, any gaseous fuel which issues from the main burner 23 will be ignited by the flame of the pilot burner 22.

Rotation of the ratchet wheel 62 by the spring 55 of the clockwork mechanism causes tensioning of the torque spring 66. When sufficient energy is supplied to the spring 66, the spring 72 will be caused to ride out of the detent notch 70, and the cam 68 can rotate approximately 180° to "pop" the cam follower 74 up, or it can rotate a lesser amount and thereafter drive the cam follower 74 up more slowly under influence of continuing action of the spring 55 of the clockwork mechanism 56 which will further tension the spring 66. These features are contemplated both ways within the scope of the appended claims.

Upward movement of the cam follower 74 causes opening of the shutoff valve 27 and movement of the armature 26 into attracted position against the magnet frame of the electromagnet. Assuming that the electromagnet 13 has been sufficiently energized during the time delay by the heat of the pilot burner flame on the thermoelectric generator, the armature 26 will remain and be held in magnetic engagement as soon as it is actuated to attracted position, and thus the valve member 27 will be held in open position. The spring 84 serves as a strain release spring which, when compressed by the cam 68, has more tension than the spring 90 and provides for firm engagement of the armature 26 with the magnet frame 14. With this structure the adjustment of the parts is preferably such that after the armature 26 engages the magnet frame 14 the cam follower 74 will preferably still be projected a short distance by the cam 68 to assure good seating of the armature against the magnet frame.

The cocking or resetting rotation of the drive shaft 54 under the action of the spring 55 of the clockwork mechanism returns the knob 58 to the position from which it is turned to tension the spring 55. Consequently, upon completion of the resetting operation by the clockwork mechanism, the parts assume their positions for subsequent operation by manipulation of the knob 58.

If the device is constructed for relatively slow action so that there might be a tendency to open the shutoff valve 27 slowly, and thereafter spend some time in fully opening this valve, flow interrupter means may, within the broader aspects of the present invention be provided for interrupting the flow of fuel for the main burner during such interval.

The opening of the valve 35 prior to closing the valve 39 assures that a supply of fuel will be established to the pilot burner 22 from the outlet chamber 7 before the supply of fuel to the pilot burner from the upstream side of the valve body 1 is shut off by the valve 39. The pilot valve structure also assures that the valve 39 is opened before the valve 35 is closed to assure that a supply of fuel to the pilot burner will be established from the upstream side of the shutoff valve before the supply of fuel to the pilot burner from the outlet chamber 7 is shut off or discontinued.

The valve 27 is closed after being fully open, for example, upon extinguishment of the flame of the pilot burner 22 with accompanying deenergization of the electromagnet 13, by the spring 90 as previously described. While as hereinbefore set forth, the cam 68 is turned through 180° by the spring of the clockwork mechanism after it is wound or tightened by turning the knob 58, it will be noted that the cam 68 due to its form will, upon approximately only 90° rotation, move the armature 26 to fully attracted position and the valve 27

to fully open position. If the electromagnet 13 is properly energized, it will hold the armature 26 attracted thereto and the valve 27 in fully open position and the spring of the clockwork mechanism will continue rotation of the cam 68 through the remainder of its 180° movement to position 180° from the position shown in Figures 1 and 3. In this position the spring 84 is released or loosened so that the spring 90 will close the valve 27 upon extinguishment of the pilot burner flame.

The embodiment of the invention shown in the drawings is for illustrative purposes only, and it is to be expressly understood that said drawings and the accompanying specification are not to be construed as a definition of the limits or scope of the invention, reference being had to the appended claims for that purpose.

I claim:

1. In combination, a first controlling member having an operating position and biased to a safety position, an igniter, a second controlling member having a position for energizing said igniter and biased to a position deenergizing said igniter, holding means for holding said first controlling member in operating position but incapable of actuating said controlling member from safety position to operating position, an energy storing device effective when energized to actuate said first controlling member to its operating position and said second controlling member to igniter energizing position, said first controlling member being held in its operating position by said holding means, and time delay means between said energy storing device and said first controlling member and providing a time delay after actuation of said second controlling member to igniter energizing position before said first controlling member is actuated to its operating position by said energy storing device.

2. In combination, a first controlling member having an operating position and biased to a safety position, an igniter, a second controlling member having a position for energizing said igniter and biased to a position deenergizing said igniter, holding means for holding said first controlling member in operating position but incapable of actuating said controlling member from safety position to operating position, an energy storing device effective when energized to actuate said first controlling member to its operating position and said second controlling member to igniter energizing position, said first controlling member being held in its operating position by said holding means, and time delay means between said energy storing device and said first controlling member and providing a time delay after actuation of said second controlling member to igniter energizing position before said first controlling member is actuated to its operating position by said energy storing device, the bias of said second controlling member being effective to bias said second controlling member to igniter deenergizing position upon completion of the actuation of said first controlling member to its operating position by said energy storing device.

3. In combination, first and second controlling members each having an operating position and biased to a safety position, an igniter, a third controlling member having a position for energizing said igniter and biased to a position deenergizing said igniter, holding means for holding said first controlling member in operating position but incapable of actuating said controlling member from safety position to operating position, an energy storing device effective when energized to actuate both of said first and second controlling members to their operating positions and said third controlling member to igniter energizing position, said first controlling member being held in its operating position by said holding means, and time delay means between said energy storing device

5 and said first controlling member and providing a time delay after actuation of said second controlling member to operating position and said third controlling member to igniter energizing position before said first controlling member is actuated to its operating position by said energy storing device.

4. In combination, first and second controlling members each having an operating position and biased to a safety position, an igniter, a third controlling member having a position for energizing said igniter and biased to a position deenergizing said igniter, holding means for holding said first controlling member in operating position but incapable of actuating said controlling member from safety position to operating position, an energy 10 storing device effective when energized to actuate both of said first and second controlling members to their operating positions and said third controlling member to igniter energizing position, said first controlling member being held in its operating position by said holding means, 15 and time delay means between said energy storing device and said first controlling member and providing a time delay after actuation of said second controlling member to operating position and said third controlling member to igniter energizing position before said first controlling member is actuated to its operating position by said energy storing device, the bias of at least said third controlling member being effective to bias said third controlling member to igniter deenergizing position upon completion of actuation of said first controlling member to its operating position by said energy storing device.

5. In combination, a first controlling member for fluid fuel burning apparatus having a main burner, an ignition burner and an igniter, said first controlling member having an operating position for flow of fuel to said main burner and biased to a safety position shutting off the flow of fuel to said main burner, a second controlling member having an operating position for flow of fuel to said ignition burner and a position in which flow of fuel to said ignition burner is shut off by said first controlling member, a third controlling member having a position for energizing said igniter and biased to a position deenergizing said igniter, holding means for holding said first controlling member in operating position but incapable of actuating said first controlling member from safety position to operating position, an energy storing device effective when energized to actuate both of said first and second controlling members to their operating positions and said third controlling member to igniter energizing position, said first controlling member being held in its operating position by said holding means, and time delay means between said energy storing device and said first controlling member and providing a time delay after actuation of said second controlling member to operating position and said third controlling member to igniter energizing position before said first controlling member is actuated to its operating position by said energy storing device.
